UNITED STATES PATENT OFFICE.

ANDREW FORMOSO, OF NEW YORK, N. Y.

PACKAGE AND ENVELOPE FASTENER.

Application filed March 22, 1926. Serial No. 96,584.

The present invention relates to improvements in envelope and package fasteners, and the primary object of the invention is to provide a fastener especially well adapted 5 for securing the flaps of envelopes together in a manner whereby ready detection may be had of prior opening of the envelope.

A further object of the invention is to provide a metallic fastener for envelopes, embodying inner and outer sections adapted to be passed through the flap of the envelope and which sections when pressed together will interlock one with the other in a manner for preventing ready separation of the 15 sections without liability of ripping or tearing that portion of the envelope flap through which the fastener extends.

Other objects and advantages of the invention will be apparent during the course 20 of the following detail description, taken in connection with the accompanying drawing forming a part of this specification and in which drawing:

Figure 1 is a perspective view of an envelope and showing the fastener sections in 25 position for sealing of the envelope when the flap is swung downwardly for closing of the envelope.

Figure 2 is a perspective view of the rear 30 side of an envelope and showing the flap in a sealed position.

Figure 3 is an enlarged longitudinal section through the envelope and one section of the fastener, and looking toward the top 35 or flap edge of the envelope.

Figure 4 is an enlarged fragmentary section taken on line 4-4 of Figure 5 looking in the direction of the arrows, and showing the fastener sections in a locked position.

Figure 5 is a view taken substantially on 40 line 5-5 of Figure 4 and looking in the direction of the arrows.

Figure 6 is a top plan view of the inner 45 plate section.

Figure 7 is a perspective view looking from the under side of the outer plate section.

Figure 8 is a perspective view of the inner plate section and looking more toward 50 the upper side thereof.

Referring to the drawing in detail, and 55 wherein similar reference characters designate corresponding parts throughout the several views, the letter A may designate an envelope of usual construction, B the outer

plate section of the fastener, and C the inner plate section of the fastener.

The envelope in the example shown, has its back consisting of the usual bottom flap 10 and side or end flaps 11 which are folded in overlying relation and sealed in the usual manner. The usual top flap 12 extends along the top edge of the envelope and is folded into overlying relation with the back of the envelope and serves as a closing means 60 for the envelope.

Referring to the outer plate section B, and which is adapted to form the outer or exposed section of the fastener when the fastener sections are in assembled relation, the 70 same embodies a disc portion 13 having a plurality of equi-distantly spaced apart prongs 14 extending from the inner side thereof. These prongs 14 are of triangular shape in formation and are preferably arranged in circular formation with their inner major surfaces facing the axis of the disc 13. The disc 13 and prongs 14 are preferably made of metal, the prongs being formed 75 integral with or secured to the disc in any suitable manner, and if desirable, an initial or other suitable matter may be printed upon the upper face of the disc as illustrated in Figure 2.

Referring now to the inner companion 80 plate section C, and which may be readily struck from sheet metal of a suitable gauge, the same is of circular shape in plan and embodies a flat disc shaped hub portion 15 about which is formed an annular concaved 85 portion 16 having its upturned peripheral edge lying in a plane with the upper face of the hub portion 15. Struck upwardly from the flat hub portion 15, is a number of equi-distantly spaced apart prongs 17 which are 90 of triangular shape, and which prongs extend upwardly from the edge portion of the hub. Struck upwardly from points near the base of the annular concaved portion 16, and extending in arcs concentric to the hub 15, are ribs 18 and which ribs as 95 will be apparent in Figures 5 and 6 are each centered with respect to the axis of a diametrically opposite prong 17, when the section C is secured to the envelope. These 100 ribs 18 and which are not severed at their ends from the portion 16, each have their intermediate portions raised a sufficient distance above the inner surface of the concaved portion 16, as to permit of passage of 105

110

the free ends of the prongs 14 beneath the ribs when the fastener sections are pressed into locking relation with one another.

In the example shown, the outer plate section B has been shown provided with three prongs 14, and the inner plate section C provided with three prongs 17 and three ribs 18 one for each of the prongs 14. This arrangement of threes has been provided so that the prongs 17 will act as a guide for the proper positioning of the outer plate section B so that one of the prongs 14 will be guided beneath each of the ribs 18. This relation of threes has been merely shown by way of example, and it will be apparent that more prongs and ribs may be provided in the companion sections in accordance with the size of the fastener and the specific use to which it is to be placed.

In use, the inside plate C may be secured in position as indicated in Figure 1, the prongs 17 being pressed outwardly through the flaps 10 and 11 and then flattened against the flaps before the contents of the envelope are positioned in the envelope. The prongs 14 of the outer plate section may then be passed through the flap 12, with the prongs 14 so positioned that when the flap 12 is swung downwardly one of the prongs 14 will be placed between two of the adjacent prongs 17. The plate B may then be pressed downwardly and by reason of the prongs 14 engaging the concave surface of the portion 16 outwardly of the hub 15, will spread outwardly with their pointed free ends extending beneath their respective ribs 18 as indicated in Figure 4. This passing of the free ends of the prongs 14 beneath the ribs 18, will prevent withdrawal of the outer plate section without liability of ripping or tearing the flap portions of the envelope. By so securing the inner plate section in position by bending the prongs 17 downwardly about the envelope flaps before sealing of the envelope by the outer section B, less pressure will be necessary for pressing of the sections into interlocking relation, as only the prongs carried by the outer section will need to be spread for the final sealing of the envelope.

It will be apparent that the prongs 14 of the section B are arranged in a circle of greater diameter than the flat hub portion 15 in order that when the sections are brought together the free ends of the prongs 14 will engage the concave surface of the annular portion 16.

From the foregoing description it will be apparent that a novel type of envelope fastener has been provided, embodying a pair of companion sections so shaped that when

the sections are forced together for final sealing of the envelope, that one of the sections will interlock with the companion section for preventing ready separation of the sections without distortion of the envelope sealed by the fastener.

Changes in detail may be made to the specific form of the invention herein shown and described, without departing from the spirit of the invention or the scope of the following claims.

I claim:

1. An envelope fastener comprising an inner section formed with a flat hub portion having upwardly extending prongs at the marginal edge thereof for attachment of the section inwardly of the rear wall of an envelope and an annular concaved portion encircling the flat hub portion with its upturned peripheral edge laying in a plane with the upper face of the hub portion, and an outer section embodying prongs adapted to be spread to extend radially by movement along the concaved portion of the inner section.

2. An envelope fastener comprising an inner section embodying a flat hub portion having prongs struck upwardly therefrom in parallel relation and spaced equidistant apart about the margin of the hub, and an annular concaved portion having elongated ribs struck upwardly therefrom and each centered with respect to the axis of a diametrically opposite prong of the hub portion when the section is secured inwardly of an envelope, and an outer section having a prong for each of said ribs, said prongs, when the sections are assembled, to be spread by the concaved portion of the inner section into locking relation one beneath each of said ribs.

3. An envelope fastener comprising an inner section formed with a flat hub portion having upwardly struck prongs at the marginal edge thereof and an annular concaved portion having equi-distantly spaced apart semi-circular shaped ribs struck upwardly in the face portion thereof concentric with the axis of the hub portion, and an outer section including a flat disc portion having equi-distantly spaced apart prongs extending from one face thereof and arranged in a circle of greater diameter than that of the hub portion of the inner section whereby when the sections are pressed together in use, the prongs of the outer section will engage the concaved surface of the inner section and be guided outwardly into interlocking relation one beneath each of the ribs of the inner section.
